POCKET

Theodore S. Tworerger, Gloversville, N. Y.

Application December 11, 1939, Serial No. 303,548

4 Claims. (Cl. 2-253)

This invention relates to new and useful improvements in a two direction and double pocket.

The invention has for an object the construction of a double pocket for a garment which is characterized by separate pockets related to each other in a particular manner.

More specifically, the invention contemplates providing an outer layer of material for the garment to carry the two directional and double pocket, and forming the outer layer with a horizontal top opening and a bottom opening spaced beneath the top opening and slanting slightly off of the vertical direction, and associated with the pockets in such a manner that these openings form the mouths for the pockets.

Still further the invention contemplates the use of a flap attached on the top edge of the horizontal opening and extending downwards to the top portion of the bottom opening.

Still further the invention proposes the use of certain edging strips attached to the edges of said pocket openings and forming supports upon which the pockets are mounted.

Another object of this invention resides in the provision of an elastic band attached at its ends upon the outer layer of material of the garment, and passing through apertures on flange portions of the pockets for holding the pockets flat against said outer layer.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure—

Fig. 1 is a front elevational view of a garment provided with two directional and double pockets in accordance with this invention.

Fig. 2 is a fragmentary enlarged detailed view of a portion of Fig. 1 showing one pair of the double pockets, and illustrated with the flap folded up and a portion of the front layer broken away to illustrate interior parts.

Fig. 3 is an enlarged detailed view of a portion of Fig. 1 to which dotted lines have been added to illustrate under parts.

Fig. 4 is a rear elevational view of Fig. 3 showing the rear parts in full lines.

Fig. 5 is a perspective view of Fig. 4.

Fig. 6 is a fragmentary vertical sectional view taken on the line 6-6 of Fig. 3.

Fig. 7 is a fragmentary horizontal sectional view taken on the line 7-7 of Fig. 3.

Fig. 8 is a rear elevational view similar to Fig. 4 but illustrating a modified form of the invention.

Fig. 9 is a similar view to Fig. 1, but illustrating another form of the invention.

The two directional and double pocket, in accordance with this invention, is intended for a garment 10 which may be of any design or construction and of any style or type of garment. This garment 10 has an outer layer of material 10^a. It is upon this outer layer that the two directional and double pocket is mounted. The outer layer 10^a has a horizontal top opening 11 having a top edge 11^a and a bottom edge 11^b. The outer layer 10^a also has a bottom opening 12 which has a side edge 12^a and an opposed side edge 12^b. This bottom opening 12 slants slightly off of the vertical direction and preferably has its upper end substantially at the center of the horizontal top opening 11.

The top edge 11^a of the top opening 11 has a flange portion 13 bent inwards. A flap 14 is provided for the pocket and has its upper edge 14^a positioned directly behind the flange 13. A line of stitches 15 engage through these parts and secure the flap to the edge of the pocket. The bottom edge 11^b of the top opening 11 has a flange portion 16 bent inwards thereof. A line of stitches 17 engages through the bent flange 16 for securing the same in position.

Edging strips 18 and 19 are respectively attached to the edges of the top opening 11. The edging strip 18 has a flange portion 18^a bent from the top thereof and located immediately adjacent the flange 16. The edging strip 19 is secured in position by the stitches 17 which engage through the strip and through the flanges 18^a and 16 and the material of the outer layer. The edging strip 19 is secured in position by the stitches 15 which pass through it. The upper edge portion of the strip 19 is arranged immediately adjacent the upper edge of the flap 14.

A pocket 20 is attached to the edging strips 18 and 19. This pocket 20 has a front layer 20^a which is secured by a line of stitches 21 to the bottom edge of the edging strip 18. The pocket 20 has a rear layer 20^b which extends upwards across the back face of the edging strip 19 and which is secured in position by the said stitches 15. It should be noted that the stitches 15 hold together the several parts as illustrated in Fig. 6, as previously explained. Another line of stitches 22 engage through the lower edge of the

edging strip 19 and the adjacent material of the rear layer 20^b of the pocket.

5 A button 24 is mounted upon the outer layer 10^a and normally engages through a button hole 25 in the flap 14 for holding the flap closed. This button 24 is located upon the edging strip 26 secured to the edge 12^b of the bottom opening 12.

10 The edge portion 12^b of the bottom opening has a flange 27 bent inwards thereof. A line of 15 stitches 28 engage through the edge 12^b, the flange 27, and a portion of the edging strip 26 to hold these parts in position. The edge 12^a has a flange 29 bent inwards thereof. An edging 20 strip 30 has one edge extended along the flange 29. A line of stitches 31 pass through the edge portion 12^a, the flange 29 and the edging strip 30 to hold these parts in position. A pocket 32 has a front layer 32^a which is secured by a line of 25 stitches to the edging strip 26. The pocket 32 has a rear layer 32^b which is secured by a line of 30 stitches 34 to the free edge of the edging strip 30.

15 The outer layer 10^a has a bottom panel 10^{aa} 20 which is secured to the adjacent upper panel by a line of stitches 36. The bottom edge portion of the pocket 32 is partially held down by this line of stitches 36 (see Fig. 4). This prevents the pocket 32 from being entirely loose behind the 25 back face of the outer layer. The pocket 29 is loose but gravity is depended upon to maintain it in a depending position.

30 In Fig. 8 a modified form of the invention is disclosed which distinguishes from the prior 35 form in the provision of a means for holding the pockets immediately adjacent the back of the outer layer of material. According to this form of the invention the pockets 32 and 20 are each provided with openings 38 through which an 40 elastic band 39 passes. This band is attached at its ends by stitches 40 to the material of the outer layer 10^a. The openings 38 are arranged in edge portions of the pockets outside of the 45 line of stitches 41 which define a side of the pocket so that the pocket is a completely closed unit except for the mouth opening thereof. It is pointed out that the pocket 32 in Fig. 8 is not held down by the line of stitches 36 which are utilized to secure the section 10^{aa} to the upper 50 section of the outer layer of material.

55 A feature of the form of the invention illustrated in Fig. 8 resides in the fact that the elastic band 39 will function to maintain the pockets flat against the back face of the outer layer. Should these pockets be moved when one places his hands therein they will be returned to their original positions by the elastic band immediately after they are freed.

60 In Fig. 9 the edging strip 26' is shown to be secured to the garment in a vertical direction. In other respects this form of the invention is similar to the previous forms.

65 While I have illustrated and described the preferred embodiments of my invention, it is to be understood that I do not limit myself to the precise constructions herein disclosed and the right is reserved to all changes and modifications coming within the scope of the invention as defined in the appended claims.

70 Having thus described my invention, what I claim as new, and desire to secure by United States Letters Patent is:

1. A pocket construction for garments, comprising an outer layer of material for the garment and having a horizontal top opening and a bottom opening spaced beneath said top opening and slanting slightly off the vertical direction, a flap attached on the top edge of the horizontal opening and extending downwards over the top portion of said bottom opening, edging strips attached on the edges of the top opening, a pocket secured to said edging strips, edging strips attached on the edges of said bottom opening, and a pocket secured to said last named edging strips, said outer layer of material having a bottom section stitched thereto, and said latter stitches being engaged through a bottom area of the last named pocket for partially holding it down. 5

2. A pocket construction for garments, comprising an outer layer of material for the garment and having a horizontal top opening and a bottom opening spaced beneath said top opening and slanting slightly off the vertical direction, a flap attached on the top edge of the horizontal opening and extending downwards over the top portion of said bottom opening, edging strips attached on the edges of the top opening, a pocket secured to said edging strips, edging strips attached on the edges of said bottom opening, a pocket secured to said last named edging strips, and an elastic band attached at its ends 20 upon said outer layer and passing through apertures on flange portions of said pockets for holding the pocket flat against the outer layer. 25

3. In a pocket construction for garments, an outer layer of material forming said garment 35 and having a horizontal top opening and a bottom opening spaced beneath said top opening and slanting slightly off the vertical direction, a pocket having the edges of its open end attached to the edges of the material defining said top opening and projected downwards adjacent the face of said outer layer, a second pocket having the edges of its open end attached to the edges of the material defining said bottom opening and projected into the space between the adjacent 40 faces of said outer layer and said first-mentioned pocket, and resilient means for holding said pockets flat against the adjacent face of said outer layer. 45

4. In a pocket construction for garments, an outer layer of material forming said garment and having a horizontal top opening and a bottom opening spaced beneath said top opening and slanting slightly off the vertical direction, a pocket having the edges of its open end attached to the edges of the material defining said top opening and projected downwards adjacent the face of said outer layer, a second pocket having the edges of its open end attached to the edges of the material defining said bottom opening and projected into the space between the adjacent faces of said outer layer and said first-mentioned pocket, and resilient means for holding said pockets flat against the adjacent face of said outer layer, comprising an elastic band 50 having its intermediate portion freely extended through apertures formed in the bottom portions of said pockets and its ends securely attached to the adjacent face of said outer layers. 55
